UNITED STATES PATENT OFFICE.

EMIL YLISTO, OF WESTERLY, RHODE ISLAND.

DILATOR.

1,331,737.

Specification of Letters Patent. Patented Feb. 24, 1920.

Application filed March 30, 1918. Serial No. 225,763.

To all whom it may concern:

Be it known that I, EMIL YLISTO, a citizen of Finland, residing at Westerly, in the county of Washington and State of Rhode Island, have invented certain new and useful Improvements in Dilators, of which the following is a specification.

This invention relates to improvements in dilators of the expanding type and its object is to provide means for dilating and exercising the vagina to enable it to more readily perform its function at the time of child birth. The invention is intended for use for a period of one month or more previous to child birth whereby the amount of pain incident to this function is minimized. With the foregoing and other objects in view the invention consists in the combination and arrangement of parts to be hereinafter fully described, pointed out in the appended claim and illustrated in the accompanying drawing which forms a part of this specification and in which—

Figure 1 is a view of my improved dilator in side elevation.

Fig. 2 is a cross section taken on line 2—2 of Fig. 1.

Fig. 3 is a fragmentary sectional view of a tubular member employed.

Fig. 4 is an enlarged fragmentary sectional view of the device.

Like reference characters denote corresponding parts throughout the several views.

My invention comprises a pair of oppositely disposed curved ribs 1, 2 of counterpart formation to the inner faces of which a plurality of bearings 3 are fixed, said bearings being arranged in oppositely disposed pairs. Each of said ribs at one end, is curved to form a nose 4. Each of the said bearings 3 pivotally carries one end of the arms 5 which arms are arranged in pairs and are pivotally secured to the collars 6, 7, 8, above and below a shaft 9, the collar 6 being formed integral with or secured to a rotary hub 10 secured by rivet 11 to a grooved portion 11^a of the said shaft and the collar 7 being movable with relation to the said shaft 9 and secured by tie rods 11^b to the said collar 8 which collar is fast to a sleeve 12 which is threaded interiorly for engagement with the threads 13 of the said shaft 9, said sleeve

being also provided with a handle 14. The said shaft 9 extends entirely through and beyond the sleeve 12 and terminates in a head 15 by means of which said shaft 9 may be rotated and moved longitudinally relatively to the said sleeve 12.

The operator by holding the handle 14 with one hand may rotate the head 15 to move the shaft 9 longitudinally of the sleeve 12 thus moving the collars 7 and 8 toward or away from the collar 6 and so, through the medium of the arms 5 expanding or contracting the dilator by the relative movement of its ribs 1, 2. Instead of rotating the head 15 the operator may hold the same stationary and rotate the handle 14 if desired to impart a rotary expanding or contracting motion to the dilator. The operator inserts the nose 4 in the vagina with the dilator in contracted position and by expanding and contracting the same in the manner previously described the organ may be exercised and stretched.

What is claimed is:—

In a dilator, a threaded shaft, a threaded sleeve arranged upon said shaft, a head carried by said shaft whereby it may be moved relatively to said sleeve while the latter is held stationary, a handle carried by said sleeve whereby it may be moved relatively to said shaft while the latter is held stationary, a hub rotative upon said shaft, a collar fixedly carried by said hub, a collar fast upon said sleeve, a third collar disposed between the aforesaid collars and fixedly connected to the collar of said sleeve, oppositely disposed ribs terminating at one end in a nose, and connection between said ribs and collars whereby movement of the latter will impart a rotary-expanding or a rotary-contracting motion to said ribs when said shaft is held stationary and a non-rotary-expanding or a non-rotary-contracting motion to said ribs when said sleeve is held stationary.

In testimony that I claim the foregoing as my own I have hereto affixed my signature in the presence of two subscribing witnesses.

EMIL YLISTO.
